POWER PLANT

Ludwig Lustig, Manhasset, N. Y.

Application June 25, 1934, Serial No. 732,196

8 Claims. (CL. 60—11)

My invention relates to power plants and particularly to power plants including an internal combustion engine and a super-charger for supplying air or an explosive mixture to the 5 engine.

In using a super-charger with an internal combustion engine the air or the explosive charge is admitted to the engine cylinder under pressure. Therefore, after explosion of the charge 10 the quantity, the volume and the temperature of the exhaust gases leaving the cylinder are considerably greater than when the super-charger is not employed. This increase in volume of the exhaust gases gives rise to considerable back 15 pressure which tends to offset the advantages gained by the use of the super-charger. For example the resistance to the passage of the large volume of exhaust gases from the cylinder presented by the valves, exhaust manifold, etc., 20 causes a substantial portion of the exhaust gases to remain in the cylinder when a new charge is admitted. In ordinary operation with a super-charger the back pressure of these gases may amount to as much as 20 or 30 lbs. per square 25 inch above atmospheric pressure. For this reason considerable difficulty is experienced in properly scavenging the cylinder preparatory to the introduction of the succeeding explosive charge. The explosive charge which is subsequently introduced into the cylinder is, therefore, 30 diluted by the remaining exhaust gases and the amount of the air or explosive mixture actually admitted to the cylinder is reduced. The force required to operate the valves and to expel the 35 exhaust gases from the cylinder is also increased when a super-charger is employed due to the increased pressure of the gases in the cylinder at the completion of the piston stroke. Furthermore, the temperature of the exhaust gases leaving the engine is higher when a super-charger is 40 employed and thus the heat contained in the gases is wasted.

In accordance with my invention the back pressure of exhaust gases leaving the engine cylinder is reduced and in fact a suction or sub-atmospheric pressure may be produced so as to aid in the removal of the exhaust gases from the cylinder. Scavenging of the cylinder is therefore improved, the amount of air or explosive mixture 45 introduced into the cylinder is increased and the force required to operate the valves and to expel exhaust gases from the cylinder is reduced.

The means employed for reducing the back pressure on the cylinder in accordance with my invention utilizes the heat contained in the ex- 50

haust gases as a source of energy for operating the same. Furthermore, this energy may also be used for operating the super-charger thus increasing the efficiency of the power plant.

In that form of my invention hereinafter described, heat contained in the exhaust gases is employed in the generation of steam for the operation of the exhauster for reducing back pressure of the exhaust gases and for operating the super-charger through the use of a turbine. 5

One of the objects of my invention is to provide a power plant including an internal combustion engine and a super-charger together with an exhauster wherein back pressure of the exhaust gases is reduced. 10

Another object of my invention is to provide mechanical means for reducing back pressure on the engine. 15

A further object of my invention is to utilize waste heat from the engine for reducing the back pressure of the exhaust gases. 20

Another object of my invention is to render the admission of air or an explosive mixture to the engine cylinders and the scavenging of the cylinders independent. 25

Another object of my invention is to provide a waste heat boiler utilizing heat in exhaust gases leaving the engine to generate steam for supplying power to actuate a super-charger for the engine and an exhauster functioning to reduce back pressure of the exhaust gases. 30

A further object of my invention is to provide means for simultaneously effecting thermal and mechanical evacuation of exhaust gases from a super-charged internal combustion engine. 35

These and other objects of my invention will appear from the following description thereof in which reference is made to the accompanying figures of the drawings illustrating typical embodiments thereof. 40

In the drawings:

Fig. 1 is a vertical sectional view of one form of power plant embodying my invention;

Fig. 2 is a vertical sectional view of a portion of the mechanism shown in Fig. 3 taken on the line 2—2 of Fig. 3; 45

Fig. 3 illustrates an alternative construction of certain elements of the combination;

Fig. 4 is a sectional view of a detail of the device shown in Fig. 3 taken on the line 4—4; and

Fig. 5 illustrates a further alternative construction adapted for use with the device as shown in Fig. 1. 50

In that form of my invention chosen for illustration in Fig. 1, the device comprises an internal 55

combustion engine 2 having a cylinder 4 and an intake manifold 6 through which air or an explosive charge is passed to the various cylinders of the engine from the conduit 8. An exhaust manifold 10 connected to the cylinders 4 through which exhaust gases are passed communicates with the exhaust conduit 12.

In order to supply the engine with air or an explosive mixture under pressure a super-charger 14 is employed. As shown, the super-charger comprises an impeller 16 mounted on a shaft 18 which is rotatable at high speed to draw air in through the opening 20 and to discharge the same to the engine cylinders under the desired pressure through conduit 8. The construction and operation of super-chargers of this type is well known and may be varied to meet the needs of any particular installation.

While the super-charger may be driven from the engine or any other suitable source of power, I prefer to relieve the engine of this burden in order to increase the power available for useful work. For this reason I utilize heat in the exhaust gases as a source of energy for the operation of the super-charger. This is effected by passing the hot exhaust gases from the engine cylinders to a waste heat boiler 22 through the exhaust conduit 12. The boiler, which may be of any suitable construction, is shown to comprise a lower chamber 24 to which the exhaust gases are admitted and with heating tubes 26 through which the hot exhaust gases pass in heat exchanging relation with water in the casing 28. The upper ends of the tubes communicate with an upper chamber 30 from which the gases are withdrawn by an exhauster as hereinafter described.

In order to pre-heat water supplied to the waste heat boiler for producing steam, I prefer to provide suitable circulating means for passing heated water from the engine cooling system to the casing 28 as needed to maintain the desired amount of water in the boiler. For this purpose the cooling system includes passages 31 extending about the cylinder walls to which cool water is admitted through an inlet 32 and from which heated water is withdrawn through an outlet 34. Water circulated in this way is preheated so that heat contained in the exhaust gases passing to the waste heat boiler is used primarily in the generation of steam and only a relatively small amount of such heat is required for raising the temperature of the boiler water. Ordinarily the boiler is not capable of converting all of the cooling water circulating through the cooling system into steam and I therefore provide the outlet 34 with a by-pass 36 for returning a portion of the cooling water to the cooling system. The remaining water is used as feed-water for the boiler and is introduced into the same by means of a pump 38 or other means, driven by a suitable controllable prime mover. The additional cold water necessary to maintain the supply of cooling water passing to the engine is supplied through a conduit 40 provided with suitable valves 41.

Steam produced by the absorption of heat from the exhaust gases passing through the waste heat boiler is utilized in the form of my invention illustrated for driving a turbine 42. Any suitable type of turbine may be employed for this purpose such as the single stage turbine illustrated. This comprises a rotor 44 having blades 46 against which steam is projected through the nozzles 48. The steam passes from the casing 28 of the boiler through the passage 50 to the annular chamber

52 which is provided with any desired number of nozzles 48 located at suitable positions adjacent the blades of the turbine.

The pressure of the steam generated in the waste heat boiler will depend largely upon the type of boiler employed, the construction and operation of the turbine and engine and various other factors. However, in order to increase the efficiency of the turbine and to obtain the maximum pressure differential on the opposite sides thereof, I prefer to provide communication between the annular exhaust chamber 54 of the turbine and suitable pressure reducing means such as an exhauster-condenser 56. Sufficient cool water is introduced into the exhauster to effectively condense the steam from the turbine so that the exhauster functions also as a condenser producing a maximum pressure differential on the opposite sides of the turbine and increasing the amount of power derived therefrom.

In order to reduce back pressure of exhaust gases passing from the engine cylinder the exhauster-condenser 56 associated with the turbine is provided with communication with the upper chamber 30 of the boiler through the passage 58. With this construction the exhaust gases after passing through the waste heat boiler wherein they are considerably reduced in temperature pass to the upper chamber 30 of the boiler and thence to the exhauster 56 through the passage 58 to the annular chamber 50 and passages 62. As shown the exhauster comprises a rotatable impeller 64 on shaft 18 by means of which the exhaust gases are forcibly withdrawn from the waste heat boiler and from the engine cylinders. The gases enter the exhauster tangentially and in the direction of rotation thereof near the center and are cooled by water introduced through inlets 66 supplied through pipes 67 shown in Fig. 2. These inlets are positioned and directed so as to bring the cold water into intimate contact with the exhaust gases and with the steam entering the exhauster-condenser through the passages 62 and 58 respectively. Furthermore the turbulence of the gases and steam in their passage from their points of introduction to the periphery of the exhauster and outlet 70 serves to insure effective cooling and condensing thereof. With this construction the temperature of the exhaust gases is reduced by the introduction of cold water into the exhauster-condenser as well as by the action of the waste heat boiler so that the temperature and volume of the exhaust gases is decreased as much as possible. This reduction in volume in the exhaust gases increases the density thereof so that the exhauster operates more effectively to reduce the back pressure on the engine. The condensate and cooled exhaust gases pass from the exhauster through the outlet 70 to a trap 12, where liquids are separated from the gases.

In the operation of the power plant shown in Fig. 1 and described above the super-charger supplies air or an explosive mixture to the engine under pressure to the cylinder of the engine where it is utilized on explosion for producing power. The resulting hot gases are withdrawn and forced from the engine cylinder upon completion of the expansion cycle by means of the exhauster 56 and the cooling and contraction of the gases in their passage through the waste heat boiler. The action of the exhauster in withdrawing the exhaust gases from the engine cylinder renders it possible to delay the opening of the intake valve somewhat since it is unnecessary to

rely upon the admission of the succeeding air, or explosive charge to assist in the scavenging of the cylinder. In other words the intake and exhaust cycles need not overlap as in present operation so that there need be no loss in the admission of unused air or explosive mixture to the cylinder.

With the arrangement described the exhauster and super-charger are carried by the same shaft 10 and driven directly from the turbine. While this construction is not essential to my invention it insures corresponding and uniform operation of the exhauster and super-charger. Thus any change in the pressure or volume of the air supplied to the engine by the supercharger is met by a corresponding change in the action of the exhauster. Furthermore, the supply of heat to the boiler from the exhaust gases is dependent in part at least on the velocity of flow of the 20 gases so that the supply of steam to the turbine is varied by the action of the other elements of the combination.

Ordinarily it will be found on starting the engine that the temperature of the boiler water 25 is low and the water from the engine cooling system is comparatively cool. The piston and cylinder walls may also be cool or cold. For this reason the temperature of the exhaust gases passing to the waste heat boiler is often much 30 lower when the engine is started than will be the case after the engine has been operated for some time. On the other hand the demand for power from the engine is frequently at a maximum on starting so that it may be important at such 35 times for the super-charger to be operated and for the back pressure of the exhaust gases to be reduced. However, although the demands for steam from the waste heat boiler are high steam is not available for proper operation of the turbine to drive the supercharger and exhauster. 40 In order to overcome this difficulty I have shown in Fig. 3 a construction for driving the super-charger and exhauster independently of the turbine until such time as the pressure of steam in the boiler has become high enough to drive the 45 turbine and operate the super-charger and exhauster satisfactorily. In this construction the shaft 74 of the turbine 42' is provided with a clutch 76 of suitable construction normally urged 50 into disengaged position by a spring 78 to permit the super-charger 14' and exhauster 56' to be freely rotated while the turbine remains stationary. The right hand member of the clutch in Fig. 3 is carried by a shaft 80 to which the 55 rotor 64' of the exhauster is keyed. The rotor 16' of the super-charger may be secured in any suitable way to a hollow shaft 84 which preferably is formed integral with the rotor for the exhauster. The means shown comprises a nut 86 cooperating with a shoulder 87 on shaft 84. The outer extremity of the tubular shaft 84 is provided with a separable coupling 88 which is connected with the shaft of an electric motor 90 for driving the supercharger and exhauster 65 independently of the turbine when the engine is being started. The coupling means employed is preferably in the form of a friction clutch adapted to provide a driving connection with the motor.

70 The clutch operating shaft 84 is axially movable within the tubular shaft alternatively to connect and disconnect the turbine and the motor to the impellers for the exhauster and super-charger. The shaft 80 is movable by means of a collar 92 rotatable with the shaft 84 but is mov-

able longitudinally thereof by means of a pivoted lever 94 having a yoke 95 engaging the collar 92. Movement of the lever 94 to the left serves to disconnect clutch 88 from the motor 90 and to move clutch member 76 into engagement to connect the turbine to shaft 80 for driving the impellers of the super-charger and exhauster. The selection of the source of power employed is preferably effected automatically in response to a condition of an element of the power plant. As shown lever 94 is actuated by means of a pressure operated device, such as the sylphon bellows 96 communicating with the upper portion of the waste heat boiler. In order to prevent free escape of steam from the boiler 15 during the starting period and to build up sufficient steam pressure in the boiler to supply the necessary power to the turbine, the bellows 96 may also serve to actuate valve 97 to admit steam to the turbine when lever 94 is moved to disengage the clutch for the motor 90 and connect the turbine to the shaft 80. Throttle 99 may also be provided to control the operation of the turbine if desired.

The lever 94 is also provided with means for 25 completing and breaking the electric circuit for energizing the motor 90 so as to maintain the motor in operation until the pressure within the waste heat boiler has reached a predetermined point, say 80 lbs. per square inch. Thereafter 30 upon the operation of the sylphon bellows, or pressure responsive means, the lever 94 is actuated and the motor energizing circuit is broken so that the turbine is substituted for the motor 35 as a source of power for driving the super-charger and exhauster and the motor is allowed to remain idle.

In the operation of the mechanism shown in Fig. 3 the lever 94 on starting the engine is in position to complete the motor circuit by engagement of the segment 98 with the contacts 100. In this position the clutch operating shaft 80 is withdrawn to the right holding clutch 88 in connected position for driving the super-charger and exhauster from the motor. The clutch member 76 is then held out of engagement with the cooperating element carried by shaft 74 of the turbine so that the turbine may remain idle. The engine is thus operated supplying air or an explosive mixture to the engine under pressure and relieving back pressure of the exhaust gases by the action of the exhauster. Heat contained in the exhaust gases is taken up by water in the waste heat boiler 22' raising the temperature thereof and converting it into steam. When the pressure 55 of the steam has reached a suitable point the pressure responsive means or sylphon bellows is actuated to open valve 97 to admit steam to the turbine and to force the lower end of the lever 94 outwardly to move the collar 92 and clutch operating shaft 80 to the left disengaging the motor clutch 88 and bringing the clutch element 76 into engagement connecting the turbine to the rotors of the super-charger and exhauster for driving the same. At the same time the circuit 60 for energizing the motor is broken by movement of the segment 98 on the lever 94 out of engagement with the contacts 100 which form a part of the motor circuit. Thus the motor remains idle when the turbine drives the super-charger and exhauster whereas the turbine is disconnected when the motor is used for driving the super-charger and exhauster. The transfer from one 65 source of power to the other for driving these elements is effected by the pressure actuated 70

means to insure proper operation of the super-charger and exhauster at all times.

- In Fig. 5 of the drawings I have illustrated alternative means for insuring proper operation 5 of the super-charger and exhauster during the initial operation of the power plant. In this construction the waste heat boiler is provided with a supplemental source of heat such as the oil or gas burner 102 projecting into the chamber 24 10 in the base of the waste heat boiler. The burner is designed to be operated to maintain the temperature of the boiler water sufficiently high to permit the immediate production of steam when the engine is started or to provide a surplus of 15 steam during the initial period of operation if this should be desirable. The supplemental heating device may be operated by a motor 104 under the control of a thermostatic device 106 responsive to changes in temperature of the exhaust 20 gases in the exhaust conduit 12. For this purpose the thermo-couple 108 is provided which as shown is located in the exhaust conduit, the mechanism used being of any suitable type such as that disclosed in the patent to Mertelmeyer 25 and Koester 1,203,230.

With this construction the supplemental heating device is operated preparatory to starting the engine so as to raise the temperature of the boiler water and generate sufficient steam to operate 30 the turbine. When the engine is started the exhaust gases are drawn through the waste heat boiler by the exhauster adding their heat to that of the supplemental heating device and acting upon the thermo-couple to reduce the supply 35 of heat from the burner 102 proportionately. As the temperature of the exhaust gases rises upon the continued operation of the power plant the requirement for heat from the burner 102 is decreased and the amount of heat provided is 40 correspondingly reduced by the action of the thermostatic device 106 until the additional heat supply is reduced to a minimum or eliminated altogether.

This construction insures a continuous supply 45 of steam for the turbine at all times when required and renders it possible to regulate the steam production to accommodate varying loads upon the power plant.

In each of the forms of my invention illustrated in Figs. 1 and 3, the turbine, exhauster and super-charger are constructed as separate 50 castings mounted upon the top of the waste heat boiler so as to present a compact inexpensive construction adapted to be readily applied to 55 existing power plants without material alteration.

While I have illustrated and described certain forms of my invention it will be apparent that my invention is not limited to the constructions 60 shown. The power plant may include two cycle or four cycle internal combustion engines of either the Diesel or Otto type. The particular form of waste heat boiler employed as well as the form of turbine, exhauster, and super-charger 65 may be varied considerably with each installation depending upon the size, cost and other factors as desired. It should, therefore, be understood that the form of power plant herein illustrated and described is intended to represent 70 a typical embodiment of my invention and is not intended to limit the scope thereof.

What is claimed is:

1. A power plant having in combination, an internal combustion engine, a super-charger for 75 said engine, a waste heat boiler utilizing heat

in exhaust gases from said engine to produce steam, a turbine for driving said super-charger and driven by steam from said waste heat boiler, an exhauster serving to reduce both the back pressure of exhaust gases of said engine and the 5 exhaust pressure of steam from said turbine, said exhauster utilizing energy from said turbine to drive the same and an alternative device driven independently of said engine and turbine for actuating said super-charger and exhauster, and means responsive to the pressure of the steam in said boiler for actuating said alternative device. 10

2. A power plant having in combination, an internal combustion engine, a super-charger for 15 said engine, a waste heat boiler utilizing heat in exhaust gases from said engine to generate steam, a turbine utilizing steam from said waste heat boiler, a rotary exhauster-condenser serving to reduce back pressure of exhaust gases from said 20 engine and to condense steam from said turbine, means for supplying cooling liquid to said exhauster-condenser, a shaft rotated by said turbine and impellers for said super-charger and said exhauster driven by said shaft. 25

3. A power plant having in combination, an internal combustion engine, a super-charger for 30 said engine, a waste heat boiler utilizing heat in exhaust gases from said engine to generate steam, a turbine for driving said super-charger and driven by steam from said waste heat boiler, an exhauster condenser driven by said turbine 35 serving to reduce back pressure of exhaust gases of said engine and to condense steam from said turbine to increase the difference in pressure on the opposite sides of said turbine, and alternative means for supplying power to drive said super-charger and said exhauster-condenser, and means responsive to the pressure of the steam in said boiler for actuating said alternative means. 40

4. A power plant comprising an internal combustion engine, a super-charger for said engine, a waste heat boiler utilizing heat in exhaust gases from said engine, an exhauster for drawing exhaust gases through said waste heat boiler, a turbine driven by steam from said boiler to actuate said exhauster and super-charger, a motor adapted to be connected to said exhauster and super-charger to actuate the same and a clutch operable to connect either said turbine or said 45 motor to said exhauster and super-charger, and means responsive to the pressure of the steam in said boiler for actuating said motor. 50

5. A power plant having in combination an internal combustion engine, a super-charger for 55 said engine, a waste heat boiler utilizing heat in the exhaust gases to generate steam, a turbine driven by steam from said boiler, an exhauster communicating with said turbine and said waste heat boiler, means for introducing a cooling medium into said exhauster to condense steam from the turbine and to cool said exhaust gases, a motor for driving said super-charger and exhauster, and means responsive to variations in the pressure of steam in said boiler to connect either said turbine or said motor selectively to the super-charger and exhauster to operate the same. 60

6. A power plant having in combination an internal combustion engine, a super-charger for 70 said engine, a waste heat boiler utilizing heat in the exhaust gases to generate steam, a turbine driven by steam from said boiler, common means for reducing back pressure on said engine and on said turbine, a motor for actuating said means 75

and super-charger and means responsive to variations in the pressure of steam in said boiler to connect either said turbine or said motor selectively to the supercharger and said means to operate the same.

7. A power plant having in combination an internal combustion engine, a super-charger for said engine, a waste heat boiler utilizing heat in the exhaust gases to generate steam, a turbine driven by steam from said boiler, an exhauster communicating with said turbine and said waste heat boiler, a motor for driving said super-charger and exhauster and means responsive to variations in the pressure of steam in said boiler to connect either said turbine or said motor selectively to the super-charger and exhauster to operate the same.

8. A power plant comprising an internal combustion engine within which a piston reciprocates, a super-charger for supplying air under pressure to said engine, a waste heat boiler utilizing the heat from the exhaust gases from said engine to produce steam, a turbine for driving said super-charger and driven by steam from said waste heat boiler, common means for reducing pressure on the exhaust side of said turbine and for reducing the back pressure of said exhaust gases from said internal combustion engine, an alternative device driven independently of said engine for actuating said supercharger and said common means, and means responsive to the pressure of the steam in said boiler for actuating said alternative device. 5 10 15

LUDWIG LUSTIG.
